UNITED STATES PATENT OFFICE.

JAMES H. BULLARD, OF SPRINGFIELD, MASSACHUSETTS.

ADJUSTABLE SHAFT-SUPPORT.

No. 845,513.

Specification of Letters Patent.

Patented Feb. 26, 1907.

Application filed March 15, 1906. Serial No. 308,101.

To all whom it may concern:

Be it known that I, JAMES H. BULLARD, a citizen of the United States of America, residing at Springfield, in the county of Hampden and State of Massachusetts, have invented new and useful Improvements in Adjustable Shaft-Supports, of which the following is a specification.

This invention has for its object the construction of a universally-adjustable fixture adapted to be secured to the steering-knuckle of self-propelled vehicles to support the end of a flexible shaft to which a pinion is secured which engages with a gear on the hub of a vehicle-wheel to actuate devices which serve to indicate the distance traveled, the circumference of the wheel serving as a unit of measure.

A further object of the invention is to provide a construction of this character all of the parts of which can be cast and assembled without being machined, thereby greatly reducing the cost thereof.

The diameter of the wheels varies on vehicles of different size and which are used for different purposes, and this necessitates a change in the diameter of a gear on the hub or the pinion which meshes with it, and it is always the pinion which is changed, of course. This therefore necessitates a fixture in which the pinion and its driving-shaft are supported which will so locate the pinion as to permit its operative engagement with the gear.

Heretofore it has been the practice to make fixtures which either have no adjustability or whose range of adjustability is very limited, thereby necessitating the manufacture of a large variety of these gear-supporting fixtures.

By means of this invention a construction is provided which is universally adjustable and may be used with any combination of gears found on the ordinary road-vehicles, its range of adjustability being so great as to not only provide for the widest variation in the gears, but also to provide for the widest variation in the location of that part of the steering-knuckle generally used on self-propelled vehicles to which the fixture must be attached in order to have it swing with the wheel.

Obviously this device is particularly adapted to use on self-propelled road-vehicles, although it may be otherwise, and in the draw-

ings it has been shown as applied to the wheel 55 of a vehicle of the class described.

In the drawings forming part of this application, Figure 1 is an elevation of the device looked at from one side; and Fig. 2 is an elevation, partly in section, of the device 60 viewed in a plane at right angles to Fig. 1. In both views it is shown in its relation to the arm of the steering-knuckle to which it is attached. Fig. 3 is a perspective view of a part of the hub of a wheel and the steering-knuckle, showing the improved adjustable 65 gear-supporting fixture applied thereto.

Referring to the drawings, *a* indicates a steering-knuckle as a whole on which a wheel *b* is mounted in the usual manner, the steering-knuckle being provided with the arms *c* and *d*, to which rods forming part of the steering mechanism of the vehicle are secured. These arms being integral parts of the steering-knuckle swing with the latter and the wheel. On the hub of the wheel is secured a gear *e*, with which a pinion *f* meshes, this pinion being supported in operative relation to the gear *e* on the fixture which forms the subject-matter of this application. This 70 fixture comprises a clamp which consists of two like parts *h*, in the lower central portion of each of which is formed a semispherical recess *k*, adapted to be clamped over the spherical end *m* of a post *o* by means of a bolt 75 *p* or the like passing through a hole in the two parts of the clamp. The upper ends of the two parts of the clamp are laterally extended and have their extremities *q* formed to partially encircle a sleeve *r*, which constitutes a bearing for a flexible shaft *s*, which is secured to the pinion *f*. The bolt *p*, which clamps the socketed portions *k* to the top of the post *o*, serves at the same time to clamp 80 the sleeve *r*. These socketed portions *k* are 85 so proportioned as to inclose a little more than one-half of the sphere *m*, to the end that the parts of the clamp may be loosened to permit the adjustment thereof in any direction without permitting its removal from 90 the post. The lower end of the latter is also spherical, as indicated by *t*, and of larger diameter than the opposite end, this end *t* having a bearing in a cap *v*, having a spherical cavity in the upper end thereof, as shown 95 very plainly in Figs. 1 and 2. The upper end of the cap has a hole through it, through 100 which the post *o* may be passed, as shown. 105

A block w is inserted in the lower end of the cap v and has a seat formed in the upper end thereof for the larger spherical end t of the post o .

5 On opposite sides of the cap v are two ears or projections x , on which hang two links y , which engage with ears on a yoke 3 beneath the arm c . In this yoke is a cavity 4 to receive a nut 5 , non-rotatably seated in said cavity, and a hole is also provided for a bolt 6 , which extends through the yoke and through the nut, the end of the bolt bearing against the arm c . The screw has no threaded engagement with the yoke, the latter being constructed as described and provided with the nut 5 to do away with the necessity of tapping the hole in the yoke. It is obvious that by screwing up the bolt 6 the cap v will be drawn down against the arm c , and thus force the block w upward, clamping the spherical end t of the post o tightly in the cap and holding the latter in any adjusted position. By slightly loosening the bolt the post o may be adjusted in any direction relative 25 to the arm c , and it may be rotated on its own axis to any degree. The clamp on the upper end of the post may also be adjusted relative to the latter in any direction.

Having thus described my invention, what 30 I claim, and desire to secure by Letters Patent of the United States, is—

1. In an adjustable fixture of the class described consisting of a post terminating in ball-bearings at its opposite ends, clamps engaging the ball-bearing at its outer end, a bearing-cap engaging the ball-bearing at its inner end, a block, a yoke, means for con-

necting the bearing-cap and yoke, and means for engaging a fixed support for drawing said cap rigidly against the block, as described. 40

2. In an adjustable clamp of the class described comprising a rigid post terminating in spherical ends, a two-part clamp inclosing the outer spherical end and affording a bearing for a flexible shaft, a screw for adjustably 45 retaining the clamp in place, a cap provided with hooks engaging the inner spherical end, a block located within the cap and also engaging the inner spherical end, and a fixed support, a yoke provided with hooks and engaging the opposite side of the fixed support, links engaging the hooks for connecting the cap and yoke together, a belt threaded through the yoke and engaging the side of the fixed support opposite the block, whereby 55 by when the bolt is rotated the cap and yoke will move in opposite directions and the block forced against the end of the rigid post and the inner spherical end clamped within the cap, as described. 60

3. In an improvement of the class described, comprising a rigid member, said member having a spherical end, means for clamping the rigid member to a fixed support comprising a cap, a block, a yoke, links 65 connecting the cap and block, the yoke and block engaging opposite sides of the fixed support, and means for moving the cap and block in opposite directions, whereby the spherical end is rigidly clamped to the cap.

JAMES H. BULLARD.
